MACHINE FOR TREATING NYLON STOCKINGS

Maurice Joseph Héliot, Troyes, France

Application April 15, 1947, Serial No. 741,640
In France July 29, 1946

14 Claims. (Cl. 223—76)

1

This invention has for its object a machine for treating nylon stockings on forming blocks inside an autoclave.

It is a well-known fact that nylon stockings should be prepared inside an autoclave and to this end treating machines have been used that include an autoclave for containing the stockings previously fitted over forming blocks.

In known machines, the autoclave should remain open during the time required for the removal of the forming blocks carrying the treated stockings and for introducing other forms carrying other stockings to be treated. The result of this manner of operating did not only lead to long stoppages during operation but also to drawbacks for the operators who had to remove the treated stockings from the inside of the autoclave and to introduce into the latter the stockings to be treated under pressure.

The invention has for its object the execution of a high efficiency machine for finishing nylon stockings, i. e., a machine for which the stoppages required for removing from the autoclave the forming blocks carrying the treated stockings and for the introduction into said autoclave of further forming blocks with the stockings to be treated, are reduced to a minimum.

A further object of the invention consists in the provision of a machine allowing the handling of the stockings whether already handled or to be handled subsequently to be performed entirely in the open with reference to the autoclave.

A further object of the invention is the execution of an arrangement for the carrying of the forming blocks, that allows a considerable increase in the number of blocks adapted to be introduced at one time into the machine and a reduction to a minimum of the time required for the handling of said blocks without this resulting in trouble of any description for the execution of the desired operations, setting of the stockings to be treated on the blocks and the removal of the treated stockings.

The above objects and others will appear more clearly from the following description and the accompanying drawings illustrating diagrammatically and merely by way of example a form of execution of the machine and carrier of the primary blocks according to the invention.

In said drawings:

Fig. 1 is an elevational partly sectional view of the machine, the two parts of the autoclave being shown spaced from each other.

Fig. 2 is a plan view of the rotary plate forming a part of the machine.

2

Fig. 3 is an elevational view of the lower part of the machine, the two parts of the autoclave being shown in their assembled position.

Fig. 4 is an elevational view of a forming block support for use with this machine.

Fig. 5 is a plan view to that of Fig. 4, the forming blocks being fitted with their stockings and ready for treatment.

Fig. 6 is a view corresponding to that of Fig. 10 5, one of the forming blocks being in a position for the introduction or removal of the stocking 15 to be treated or already treated as the case may be.

In the embodiment illustrated in Figs. 1 to 3 15 the chief components of the machine are constituted by a rotary plate 1 and by an autoclave made of two parts, namely a body or bell-shaped part 2 including a welded dome and a bottom 3.

The rotary plate 1 that in the illustrated modification of the invention has an outline shaped 20 as an equilateral triangle with rounded corners includes three zones defined by three circles C, C' and C'' the diameter of which is substantially equal to the inner diameter of the body 2. Each 25 of these three zones is adapted to receive the stockings to be treated, either on individual and independent forming blocks or preferably on forming blocks rigidly connected with a common carrier, as hereinafter described.

The plate 1 is provided with a central opening 4 allowing it to be rotated about a stationary tubular upright 5 forming part of the frame of the machine. Said plate rests freely on a socket 6 also mounted so as to be capable of rotation relative to upright 5 and provided at its lower 35 end with a gear 8 adapted to be rotated by any suitable means.

Although the plate 1 rests freely on the socket 6 it is capable of taking part in the rotation of the latter through the cooperation of studs 9 40 provided in the upper surface of said socket and engaging corresponding openings 10 provided in the plate 1.

The body 2 which should be vertically movable 45 above the plate 1 is mounted at the upper end of a rod 11 rigidly connected with a piston 12 housed inside the tubular upright 5. In the illustrated modification of the invention the piston 12 is controlled hydraulically and the inlet and outlet of the control fluid into said upright 50 are obtained through the pipes 13 and 14. As shown, the body 2 is guided in its displacements by means of rollers 15 adapted to move over a suitable raceway such as 16.

At its lower end, the body 2 of the autoclave 55 is provided with four hooks 17. The two hooks

17 which are the nearest the upright 5 are adapted to pass through slots 18 provided in the plate 1 whereas the two other hooks pass outside the periphery of the plate 1.

The body is completed by a fluid-tight packing 19 located on the periphery of its lower surface.

The bottom 3 that should be vertically movable underneath the plate 1 is carried by the upper surface of a piston 20 adapted to move inside a cylinder 21 and controlled preferably through hydraulic means. Said bottom is provided with a passageway 22 for any liquid or gas required for the treatment of the stockings in the autoclave.

Over the cylinder 21 is arranged a rotary ring provided with four hooks 23 corresponding as to shape and size with the hooks 17 provided on the body 2. Furthermore a fluid-tight packing 24 is provided throughout the upper periphery of the bottom 3.

The control of the rotary plate 1 is executed in a manner such that said plate may be held fast with reference to the two part autoclave in three positions for each of which one of the zones defined on said plate is correctly positioned in a manner such that the stockings on the forming blocks carried by the plate may be treated inside the autoclave.

Supposing the autoclave is open as shown in Fig. 1 and the zone C has been brought into its treating position, the working of the machine is as follows:

The body 2 is lowered and at the same time the bottom 3 is raised. When these two parts of the autoclave are at the end of their stroke, the packing 19 of the body 2 is strongly pressed against the upper surface of the plate 1 while the packing 24 on the bottom 3 is energetically pressed against the lower surface of said plate. The latter is thus strongly held between two parts of the autoclave that may be locked in this position by bringing through a rotation of the rotary ring the hooks 23 into engagement with the hooks 17 (Fig. 3).

The operation is now finished by introducing into the body 2 the liquid, vapour or gas required for the treatment of the stockings and entering the body 2 through the channel 22 and the opening 25 provided in the plate 1 at the centre of each of the zones C, C' and C''.

While the stockings in the zone C are undergoing treatment, it is possible to introduce inside the zone C'' the stockings which are to be treated after the opening of the autoclave and rotation of the plate through 120°. As to the stockings located in the zone C', they have been treated just before those now undergoing treatment in the zone and they are allowed to cool or they are removed from their forming blocks.

When the treating period of the stockings inside the autoclave is at an end it is sufficient to raise the body 2, to lower the bottom 3 and to make the plate rotate in a manner such that the zone C'' may take the place of the zone C with reference to the autoclave whereby the stockings located in said zone C'' may in their turn be submitted to treatment as disclosed.

The consequence of this is that the machine stops just during the time required for opening the autoclave, for rotating the plate 1 through 120° and for closing said autoclave. The stoppages in the useful operation of the machine are therefore very short and it is possible to state that the machine operates in practice in a con-

tinuous manner. Moreover no handling of the stockings or of the forming blocks is performed inside the autoclave as the removal of the stockings from and the fitting thereof on the blocks 6 are operated in succession in the positions C' and C'', unless it is preferred to provide these two operations both in the positions, the position C'' serving only for the cooling of the stockings passing out of the autoclave.

10 In order to allow using to the utmost either of the zones C, C', C'', the invention covers also an arrangement forming a block carrier as illustrated more particularly in Figs. 4 to 6.

This arrangement is constituted by a suitable number of metallic forming blocks 31, say twelve;

15 each of these supporting blocks is executed in the usual manner and is rigidly secured at its lower end through rivetting, welding or otherwise to a pivoting holder 32 provided at one side with hinge eyes 33 and 34. These hinge eyes 33 and 34 support a vertical spindle 35 rigid with two rings 36 and 37 of which one is secured to a circular base plate 38 having a diameter smaller than that of the circles C, C', C'' of the swiveling plate 1.

20 During operation, the forming blocks assume the position in which they are illustrated in Fig. 5, i. e. they are uniformly distributed around the central part of the plate 38 and said blocks may be held in this position by suitable bolting means. On the contrary when it is desired to remove the stockings from any of the blocks 31, the latter may be isolated from the others as apparent from Fig. 6.

25 The arrangement of Figs. 4 to 6 for a given number of blocks is less spacious than if individual blocks are used the number of which is equal to that provided in the case considered by the invention. It is therefore possible to treat 40 in a single operation inside the machine autoclave a larger number of stockings than if it were desired to use for the latter independent individual blocks. Moreover the time required for introducing and removing the stockings on and off the forming blocks inside the treating apparatus is considerably reduced.

The machine and the arrangement carrying the forming blocks as described may form the object of numerous modifications without widening the scope of the invention as defined in accompanying claims. Thus although a hydraulic control has been provided for the relative displacements between the two parts of the autoclave, the control may be executed through any mechanical, electrical or even hand-operated means.

55 Furthermore the shape of the plate may be different from that disclosed and include more than three zones in the case where this may appear to be useful. As for the holder arrangement forming the support of the blocks, obviously the number of blocks carried by said holder may be different from that disclosed; similarly also, it is possible to provide a holder of a different shape carrying for instance oblique axes. Lastly, instead of using a base plate of circular shape, said plate may be given any other suitable shape in accordance with the shape given to the plate 1 of the machine.

60 What I claim is:

70 1. A machine for the treatment of nylon and the like hosiery on forming blocks comprising an autoclave consisting of an upper and a lower part, means to move said two parts vertically relative to each other, a plate carrying the forming blocks 65 in different angular locations being located for

rotation through the horizontal plane in which the said two autoclave parts upon their vertical approach meet and a vertical plate-supporting shaft being rotatably located at the outside and near the autoclave whereby the forming blocks secured on said plate are moved into identical operating positions relative to the said autoclave parts.

2. A machine for the treatment of nylons and the like hosiery on forming blocks comprising an autoclave consisting of an upper and a lower part, means to move said two parts vertically relative to each other, a plate carrying the forming blocks in different angular locations being located for rotation through the horizontal plane in which the said two autoclave parts upon their vertical approach meet the said plate having a substantially polygonal shape the forming block being located in the corner portions of said plate and at an equal distance from its center point and a vertical plate-supporting shaft being rotatably located at the outside and near the autoclave whereby the forming blocks secured on said plate are moved into identical operating positions relative to said autoclave parts.

3. A machine for the treatment of nylons and the like hosiery on forming blocks comprising an autoclave consisting of an upper and a lower part, means to move said two parts vertically relative to each other, a plate carrying the forming blocks in different angular locations being located for rotation through the horizontal plane in which the said two autoclave parts upon their vertical mutual approach meet the said plate having a substantially triangular shape, the forming blocks being located in the corner portions of said triangle and at an equal distance from the center point of the plate and a vertical plate-supporting shaft being rotatably locked at the outside and near the autoclave whereby the forming blocks secured on said plate are moved into identical operating positions relative to the autoclave parts.

4. A machine for the treatment of nylon and the like hosiery on forming blocks comprising an autoclave including an upper and a lower part adapted to move vertically with reference to one another and a horizontal swivelling plate adapted to carry in different angular locations the forming blocks, a vertical shaft arranged on the outside and near the autoclave and on which the plate is coaxially fitted, a socket coaxial with and fitted over said shaft, means for driving said socket through a predetermined angle, means whereby the socket carries the plate along with it for causing a predetermined sector of the plate to lie between the two parts of the autoclave together with the forming blocks and hosiery carried by said blocks.

5. A machine for the treatment of nylon and the like hosiery on forming blocks comprising an autoclave including an upper and a lower part adapted to move vertically with reference to one another, a horizontal swivelling plate assuming a substantially polygonal shape adapted to carry the forming blocks in each of the locations defined by a circle, the centre of which lies on the bisecting line of an apex of said polygon, and located in the plane in which the two parts of the autoclave are adapted to meet when moving near one another, the vertical swivelling axis of said plate lying outside the autoclave for allowing the successive location in register with the autoclave parts of the blocks carried by the differ-

ent portions of the plate and means for admitting a hosiery treating fluid through the lower part of the autoclave and through the centre of each circle drawn on the plate.

5. A machine for the treatment of nylon and the like hosiery on forming blocks comprising an autoclave including an upper and a lower part adapted to move vertically with reference to one another, a horizontal swivelling plate adapted to carry in different angular locations the forming blocks and located in the plane in which the two parts of the autoclave are adapted to meet when moving near one another, the vertical swivelling axis of said plate lying outside the autoclave for allowing the successive location in register with the autoclave parts of the blocks carried by the different portions of the plate and means for controlling the relative vertical movements of the two parts of the autoclave and for holding said parts in fluid-tight relationship with the corresponding sides of the part of the plate registering with them.

7. A machine for the treatment of nylon and the like hosiery on forming blocks comprising an autoclave including an upper and a lower part adapted to move vertically with reference to one another, a horizontal swiveling plate adapted to carry in different angular locations the forming blocks, a hollow shaft arranged on the outside and near the autoclave, and on which the plate is coaxially fitted, a socket co-axial with and fitted over said shaft, means for driving said socket through a predetermined angle, means whereby the socket carries the plate along with it for causing a predetermined sector of the plate to lie between the parts of the autoclave together with the forming block and hosiery system carried by said sector, a piston adapted to reciprocate inside said hollow shaft and rigid with the upper part of the autoclave and means for controlling through a fluid the movements of said piston inside the hollow shaft for urging the upper part of the autoclave into and out of fluidtight relationship with the plate.

8. A machine for the treatment of nylon and the like hosiery on forming blocks comprising an autoclave including an upper and a lower part adapted to move vertically with reference to one another, a horizontal swivelling plate adapted to carry in different angular locations the forming blocks, a hollow shaft arranged on the outside and near the autoclave, and on which the plate is co-axially fitted, a socket co-axial with and fitted over said shaft, means for driving said socket through a predetermined angle, means whereby the socket carries the plate along with it for causing a predetermined sector of the plate to lie between the two parts of the autoclave together with the forming block and hosiery system carried by said sector, a piston adapted to reciprocate inside said hollow shaft and rigid with the upper part of the autoclave and means for controlling through fluid movements said piston inside the hollow shaft and urging thereby the upper part of the autoclave into fluidtight relationship with the plate, rollers carried by the upper part of the autoclave and guideways arranged vertically along the tubular shaft for co-operation with said rollers.

9. A machine for the treatment of nylon and the like hosiery on forming blocks comprising an autoclave including a lower part and an upper part adapted to move towards and away from said lower part, hooks rigid with both parts and

adapted to interengage for holding the two parts in their adjacent operative position, a horizontal polygonal plate adapted to swivel round a vertical axis lying near and on the outside of said autoclave, and adapted to carry in a plurality of angular positions forming blocks with hosiery fitted over same, said plate being provided with apertures for the snug passage of at least the inner hooks on the upper part and packings on the edges of the two parts of the autoclave facing one another for fluidtightly holding between them the portion of the plate carrying hosiery that registers with them at the time considered.

10. A machine for the treatment of nylon and the like hosiery on forming blocks comprising an autoclave including an upper and a lower part adapted to move vertically with reference to one another, a horizontal plate located in the plane in which the two parts of the autoclave are adapted to meet when moving near one another, said plate being adapted to rotate round an axis lying outside and near the autoclave and to carry in a plurality of angularly shifted positions the forming blocks for the hosiery, said plates having a radius extending beyond the furthest point of the autoclave, means for moving the upper part of the autoclave into fluidtight relationship with the plate over a forming block thereon, a piston rigid with the lower part of the autoclave, a cylinder in which said piston is adapted to reciprocate, means for controlling the piston and means for passing a treating fluid into the lower part of the autoclave and through the different operative positions of the plates.

11. A machine for the treatment of nylon and the like hosiery on forming blocks comprising an autoclave including a lower part and an upper part adapted to move towards and away from said lower part, hooks rigid with both parts and adapted to interengage for holding the two parts in their adjacent operative position, a horizontal polygonal plate adapted to swivel round a vertical axis lying near and on the outside of said autoclave, and adapted to carry in a plurality of angular positions forming blocks with hosiery fitted over same, said plate being provided with apertures for the snug passage of at least the inner hooks of the upper part, packings on the edges of the two parts of the autoclave facing one another for fluidtightly holding between them the portion of the plate carrying hosiery that registers with them at the time considered, and means for angularly shifting the lower hooks round the axis of the autoclave.

12. A machine for the treatment of nylon and the like hosiery on forming blocks comprising an autoclave including an upper and a lower part adapted to move vertically with reference to one another, a horizontal plate located in the plane in which the two parts of the autoclave are adapted to meet when moving near one an-

other, said plate being adapted to rotate round an axis lying outside and near the autoclave and to carry in a plurality of angularly shifted positions the forming blocks for the hosiery, said plates having a radius extending beyond the furthest point of the autoclave, means for moving the upper part of the autoclave into fluidtight relationship with the plate over a forming block thereon, a piston rigid with the lower part of the autoclave, means for controlling the piston, downwardly projecting hooks rigid with the upper part of the autoclave, a plurality of upwardly directed hooks adapted to engage the first mentioned hooks, a ring carrying said lower hooks and adapted to swivel at the periphery of the cylinder enclosing the piston controlling the lower part of the autoclave, and means for preventing any relative vertical movement between the cylinder and the hook carrying ring, the inter-engagement of the two series of hooks providing for the fluidtight securing of the two parts of the autoclave to either side of the plate.

13. In a machine as claimed in claim 1, the provision of a plurality of forming blocks, a number of holders each carrying a forming block, base plates, a support rigid with and axially carried by each base plate, means for pivotally securing the block-carrying holders through vertical generating lines to the corresponding support, means for securing the different base plates in angularly spaced relationship with reference to the swivelling plate of the machine and means for locking the holders of the supporting blocks in the desired angular position with reference to the base plate.

14. In a machine as claimed in claim 1, the provision of a plurality of forming blocks, a number of holders each carrying a forming block, base plates, supports including two superposed annular members and uprights connecting same together, means for pivotally securing the holders to corresponding support uprights, means for securing the different base plates in angularly spaced relationship with reference to the swivelling plate of the machine, means for locking the holders in the desired angular position with reference to the corresponding support and means for securing the lower annular members of the supports to the corresponding base plates co-axially therewith.
